UNITED STATES PATENT OFFICE.

JESSE B. SCOTT, OF KANSAS CITY, KANSAS, ASSIGNOR TO THE AD-PENCIL COMPANY, OF KANSAS CITY, MISSOURI, A CORPORATION OF MISSOURI.

PENCIL-PRINTING MACHINE.

1,080,722.

Specification of Letters Patent.

Patented Dec. 9, 1913.

Application filed November 9, 1912. Serial No. 730,415.

To all whom it may concern:

Be it known that I, JESSE B. SCOTT, a citizen of the United States, residing at Kansas City, in the county of Wyandotte 5 and State of Kansas, have invented certain new and useful Improvements in Pencil-Printing Machines, of which the following is a specification.

This invention relates to pencil printing 10 machines, and has for its object to produce a machine by which pencils can be expeditiously and rapidly printed in two colors.

A further object is to produce a machine 15 of this character in which the pencil is printed by being rolled over the form, and which, as the printing operation is completed, is released.

Another object is to provide means for 20 inking both forms preliminary to each printing operation.

With these general objects in view, and others as hereinafter appear, the invention consists in certain novel and peculiar features of construction and organization as 25 hereinafter described and claimed; and in order that it may be fully understood reference is to be had to the accompanying drawings, in which—

Figure 1, is a top plan view of a two-color 30 pencil printing machine, embodying my invention. Fig. 2, is a side view of the same. Fig. 3, is a central longitudinal section of the machine with the ink-distributing rollers in the position they occupy when inking the 35 forms, and with the pencil rolling appliance, automatically raised to inoperative position to avoid interfering with the inking of the forms. Fig. 4, is a top plan view of the machine with the pencil rolling mechanism 40 swung to an upright position, the form and bed plate being omitted to disclose the underlying mechanism. Fig. 5, is a detail perspective view of one of the inking-disk-carrying bars. Fig. 6, is a detail perspective 45 view of a cam-carrying rock-lever forming part of the machine.

In the said drawings, 1 indicates the base 50 of the machine, 2 the side walls formed to provide a pair of upwardly projecting standards 4.

5 is a series of bolts connecting the semi-

hexagonal standards, and secured to said bolts are bars 6, the outer faces of which preferably parallel the upwardly converging edges of the standards 4.

7 is a disk arranged with its outer face paralleling the adjacent inclined edges of the semi-hexagonal standards, and provided with a spindle 8, journaled in the adjacent bar 6, and retained in position by 60 a washer 8^a, and a key 9, and said disk is provided at its inner side with a series of radial teeth 10. A similar disk 11, is arranged with its outer face parallel with the other inclined edge of the semi-hexagonal 65 standards and is provided with a spindle 12 journaled in the adjacent bar 6, and is retained in position by a washer 13, and a key 14, and said disk 11, is provided at its inner side with radial teeth 15.

70 16 is a crossbar connecting the semi-hexagonal standards centrally between the disks 10 and 11, and 17 is a horizontal rock lever carried by and underlying lever 16, and equipped at its rear end with a pivoted dog 75 18, adapted under the action of spring 19 to lie in the path of teeth 10, of disk 7, and to be capable of yielding so as to slip over said teeth when the lever rocks in one direction. A similar dog 20 is mounted on the other 80 end of the rock lever 17, and is held by a spring 21 in position to engage the teeth 15 of disk 11.

22 is a cam plate depending from rock lever 17, and provided with a flange 13 at 85 its upper end, underlying and secured to said rock lever by rivets 24.

25 is a rocker shaft journaled in the semi-hexagonal standards of the frame, and provided with an arm 26, which in each rock- 90 ing action of said shaft, engages the cam 22 and thus operates the rock lever. The first operation, which occurs as the rock arm swings forward or to the right, imparts rotatable movement to disk 7 and seats dog 20 95 in engagement with a tooth of disk 11. On the back movement said arm strikes the rear portion of the cam and rocks the lever back to its initial position, and in so doing returns dog 18 to its initial position and imparts 100 rotation to disk 11 through the instrumentality of dog 20.

To impart movement to rock shaft 25, it is provided with a gear wheel 27 meshing with gear wheel 28 mounted on rock shaft 29 which is equipped at one end with an operating handle 30.

Secured to the outer side of each semi-hexagonal standard by screw bolts 31 is a pair of semi-hexagonal shaped tracks 32 and 33, the tracks 32 being interposed between said standards and tracks 33. The tracks 32 and 33 are of identical construction but are arranged in reversed positions, so that the left hand edges of tracks 33 project rearwardly beyond the corresponding edges of tracks 32, and the right hand edges of tracks 32 project forwardly beyond the corresponding edges of tracks 33, it being also noted that the right hand ends of the upper portions of tracks 32 and the left hand ends of the abutting upper portions of tracks 33, respectively, project above the upper edges of the remaining portions of said tracks as at 34 and 35 respectively, and that the adjacent ends of said portions 34 and 35 are inclined, as shown clearly in Fig. 2.

At opposite sides of the frame, the shaft 25 carries a pair of I-shaped frames 36, the stem portions of said frames extending through said shaft and being secured rigidly thereto by nuts 37, whereby said I-frames are clamped tightly against the shaft.

38 is a pair of rods slidably mounted in the frames 36 and terminating at corresponding ends in hooks 39, forming journals for the ends of the spindle of an inking roller 40, and said roller is provided with track rollers 41 to travel upon the tracks 32, and to hold said rollers in engagement with said tracks, springs 42 are mounted upon rods 38 and exert pressure at their opposite ends against the frames 36 and collars 42^a mounted on rods 38.

43 are rods extending slidably through frames 36 and terminating at corresponding ends in hooks 44 forming journals for the spindle of the inking roller 45, and said roller is provided with track rollers 46 engaging tracks 33, and held in engagement with said tracks by springs 47 mounted on rods 43, and bearing against frame 36 and collars 48 of said rods 43.

49 are spacer strips mounted upon the standards 4, and bridging the space therebetween, and secured upon the strips 49, is a bed plate 50, upon which is mounted a chase 51, in which is secured as shown or in any other suitable manner, a pair of forms 52 and 53 the same extending in parallel relation and transversely of the machine.

From the foregoing it will be apparent that by rocking handle 30 to the left, shaft 25 is turned in the direction indicated by the arrow Fig. 3, and as hereinbefore ex-

plained, turns disk 7 one step. Said movement of shaft 25 is participated in by frames 36, so that the inking rollers travel upwardly, then horizontally and then downwardly, substantially parallel with the edges of the semi-hexagonal standards 4. In the upward movement, the roller 40 operates in engagement with the face of the disk 7, and receives ink therefrom, the roller 45 traveling in the same direction but above

70

and out of contact with said disk. As the rollers travel over the top of the standards 4, the rollers 41 first travel upon the depressed portions of tracks 32 so that the roller 40 shall engage and ink the form 52,

75

and as it clears said form, said track rollers 41 ride upwardly on the elevated portions 34 of said tracks, so that during the remainder of the travel in the direction indicated, that is forward, roller 40 shall pass

80

over form 53 without touching the same, it being also noted that as rollers 41 travel downwardly on the tracks 32, the roller 40 cannot contact with disk 11. In the same operation, the rollers 46, travel over the

85

elevated portion 35 of tracks 33, and then descend onto the depressed portions of said tracks, and the roller 45 being in advance of roller 40, is carried over form 52 without contact therewith and then drops down into

90

engagement with form 53, and during the remainder of its forward travel, comes into contact with and receives ink from disk 11. As the handle 30 is thrown back to its initial position, the rollers are returned to

95

their original positions and at the same time the rock lever, as hereinbefore explained, imparts rotation to disk 11, the track rollers and inking rollers reengaging in their return movement, the same parts

100

which they engaged in their forward movement, it being understood that the track rollers drop down from the high portions of the tracks to the low portions through the retractile action of their respective springs, and, said springs yield to permit the track rollers to climb the high portions of the tracks.

105

56 is a cross bar connecting standards 3, and hinged thereto at 57 is a plate 58, provided with a pair of forward arms 59, which, when the plate is horizontal, overlie the chase at the opposite sides thereof, the said arms having depending strips 60 to

110

rest upon the form when the printing operation is in progress, and one of the arms 59 is provided with an extension 61 terminating in an upwardly projecting stop 62 for a purpose which hereinafter appears, and both of said arms are provided at their upper sides with thin friction tracks 63, whereby the possibility of slippage of a pencil being printed, is guarded against.

115

64 is a pair of parallel walls rising from plate 58, and 65 is a plate secured thereto

120

and terminating forward of plate 58 in an arm 66, which constitutes an abutment or gage against which each pencil to be printed, is thrust, in order that the printing of 5 the pencils shall begin at the same distance from the butt end thereof.

67 is a bar secured to plate 58, and about midway the length of said plate, said bar is bent outwardly and then extends forwardly at 68 and at its free end is bent upwardly slightly at 69 so as to lie above a pin 70 projecting inwardly from handle 30, so that when the handle is swing to the left, the pin shall engage bar 68 and swing 10 the plate 58 upwardly to give the inking rollers free passage over the disks and the forms. As the rollers descend over disk 11 plate 58 drops downward to its original position. As the movement of the handle 15 is reversed, the pin 70 again engages rod 68 and swings plate 58 upwardly to permit the inking rollers to pass back to their original positions. As the rollers start downward, the plate 58 drops back to its original 20 position.

71 are retainer clips secured to and projecting inwardly from walls 64 over a slide plate 72 fitting between walls 64 of plate 58. 73 are springs interposed between said 25 plates, and disposed so as to hold the front end of plate 72 elevated above plate 58 a distance in excess of the diameter of a lead pencil, and said plate 72 is provided at its under side in the vertical plane of friction 30 track 63, with friction tracks 74. Near its rear end and centrally between its side margins, plate 72 is provided with a spacing head 75 adapted to slide back and forth upon plate 58 during and after each printing operation, 35 as hereinafter explained, and projecting upwardly from the rear end of plate 58 is an arm 76, the same being secured to plate 58 by a clamping screw 77.

78 is a retractile spring secured at its 40 rear end to standard 76 and at its front end to a standard 79 projecting upwardly from plate 72 near the front end of the latter, and said spring tends to hold plate 72 thrown back against standard 76, as shown in Fig. 3.

80 is a standard mounted upon plate 72 near its rear end, and said standard in conjunction with standard 79, forms a support for a tubular handle 81, which incloses 45 spring 78 for the greater part of its length.

85 To accommodate the device for operation with pen holders, screws 82 extend up through the right hand track 74 and through transverse slots 83 in slide plate 72, the slots accommodating lateral adjustment of 50 said trackway, and nuts 84 engage said screws 82 to rigidly secure said track at the desired point of adjustment along the length of said slots. It is obvious that where one extremity of an object, such as a penholder, 55 is tapered, one of the tracks 74 must be

shifted so as to engage a part of the object where it is of the same diameter as where engaged by the other track 74, otherwise the object or penholder would not maintain its position at right angles to its direction of 60 travel upon the friction tracks 74.

Assuming that the parts are in position shown in Fig. 1, and that the lead pencil to be printed is placed upon the tracks 63 and against the front end of walls 64 and 65 with one end against the gage 66, it will be apparent that by reference to Fig. 3, that the front ends of tracks 74 will overlie the pencil, as shown in full lines Fig. 2, and dotted lines, Fig. 1.

Assuming that the form has just been inked, the operator grasps handle 81, and applying pressure thereon to cause tracks 74 to engage the pencil, slides said plate forwardly and thus causes the pencil to roll in the same direction, the forward movement of the plate being limited by contact with the stop 62, at the same moment that the pencil after making two complete revolutions, reaches the front extremity of the 70 arms 59, from which it rolls or is caught by a conveyer (not shown) or by hand. At the same time the handle of the slide plate is released to permit the spring 78 to return the former to its initial position, the 75 spring 73 again raising its front end so that a second pencil may be placed in operative position. Immediately after the slide plate returns to its original position, the operator rocks handle 30 to the left and back again, 80 for the purpose of reinking the forms, it being understood that the disks may be inked by hand or in any other suitable manner, and that the inks will be of different shades or colors, one of the colors being 85 printed on the pencil on the first revolution of the latter and the other color in the second revolution.

From the above description it will be apparent that I have produced a pencil-printing machine embodying the features of advantage enumerated as desirable and I wish it to be understood that while I have illustrated and described the preferred embodiment of the invention, I do not desire to be 90 restricted to the form, proportion, detail construction and organization shown and described, but reserve the right to make all changes properly falling within the spirit and scope of the appended claims.

I claim:

1. In a machine for printing cylindrical objects a supporting plate for a pair of printing forms, a pair of inking rollers, means for moving said rollers back and forth over 95 said forms, guiding means whereby one of said rollers shall be permitted to engage one of said forms and be lifted to clear the other form, and the companion roller will be lifted to clear the first-named form and 100

permitted to engage the other form, and means for rolling a cylindrical object over said forms.

2. In a machine for printing cylindrical objects, a supporting plate for a pair of printing forms, a pair of inking rollers, means for moving said rollers back and forth over said forms, yielding means for pressing the rollers toward the forms in

10 their passage over the latter, guiding means whereby one of said rollers shall be permitted to engage one of the forms and prevented from engaging the other, guiding means whereby the companion roller shall be prevented from engaging the form engaged by the first-named roller and permitted to engage the other form, and means for rolling a cylindrical object over said forms.

3. In a machine for printing cylindrical objects, a supporting plate for a pair of printing forms, a pair of inking devices, a pair of inking rollers, means for moving said rollers back and forth over said forms and inking devices, guiding means whereby 25 one of said rollers shall be permitted to engage one of the inking devices and one of the forms and raised above the other form and inking device in each of the movements of the said roller, and the other roller shall be caused to travel over the first-named inking device and form without contact therewith and lowered to engage the other form and inking device in both movements of said roller, and means for rolling a cylindrical object over said forms.

4. In a machine for printing cylindrical objects, a supporting plate for a pair of printing forms, a pair of inking devices, a pair of inking rollers, means for moving 40 said rollers back and forth over said forms and inking devices, guiding means whereby one of said rollers shall be permitted to engage one of the inking devices and one of the forms and raised above the other form and inking device in each of the movements of the said roller, and the other roller shall be caused to travel over the first-named inking device and form without contact therewith and lowered to engage the other form and inking device in both movements of said roller, and means for automatically imparting rotary movement to one of the devices as the rollers travel in one direction and similar movement to the other inking 55 device as the rollers travel in the other direction.

5. In a machine for printing cylindrical objects, a supporting plate for a pair of printing forms, a pair of inking devices, a pair of inking rollers, means for moving 60 said rollers back and forth over said forms and inking devices, yielding means tending to constantly press the rollers toward the inking devices and forms in the passage of the former over said devices and forms,

guiding means whereby one of said rollers shall be permitted to engage one of the inking devices and one of the forms in both movements of the said roller, guiding means whereby the other roller in both of its 70 movements shall be permitted to engage the other inking device and form, and means for rolling a cylindrical object over said forms.

6. In a machine for printing cylindrical objects, a supporting plate for a pair of printing forms, a pair of inking disks provided with teeth, a rock lever, spring-actuated dogs carried by said rock lever for engagement with the teeth of said disks, a rock 75 shaft between the disks and below said plate, frames carried by said rock shaft, a pair of inking rollers carried by said frames, springs tending to press said frames toward said shaft, means whereby said shaft can be 80 oscillated to cause the inking rollers to travel back and forth over said inking disks and said forms, means whereby the movements of said shaft shall rock said lever and through said dogs alternately rotate said disks, and guiding means whereby one of said rollers in each of its movements is permitted to engage one of the disks and one of the forms and prevented from engaging the other form and other disk, and the 85 companion roller is permitted in each of its movements to engage the said other disk and other form and is prevented from engaging the disk and form engaged by the 90 roller first referred to.

7. In a machine for printing cylindrical objects, a supporting plate for a pair of printing forms, tracks at opposite sides thereof upon which a cylindrical object is adapted to be rolled over and in successive 105 contact with said forms, a pair of inking rollers, means for causing the same to travel back and forth over and apply ink to different forms, and means movable with said rollers for raising said tracks upwardly 110 above the rollers as the latter pass in either direction over said forms.

8. In a machine for printing cylindrical objects, a supporting plate for a pair of printing forms, a pair of hinged tracks at 115 opposite sides of said forms, a rod movable with said tracks and disposed outward of one of them and extending forward and downward with respect thereto and terminating in an upwardly flaring front end, a 120 rock shaft, a pair of inking rollers movable back and forth with said shaft and over said forms and each adapted to ink one of said forms, a lever for operating said shaft, and a pin projecting from said lever and 125 adapted when the latter swings in one direction to engage the flaring end of said rod and raise the hinged tracks above the plane of movement of the inking rollers as the same pass rearwardly over the forms 130

and adapted to also engage said rod and raise the tracks out of the path of the rollers as the latter move forwardly over said forms.

- 5 9. In a machine for printing cylindrical objects, a pair of tracks upon which a cylindrical object may roll, means to hold a pair of forms between said tracks so that the rolling object shall contact with the forms, means for supplying said forms with inks of different colors, means for engaging the upper side of and rolling such object over the forms and said tracks, and a stop to arrest the movement of said means after the object has been rolled beyond the forms.
- 10 15. 10. In a machine for printing cylindrical objects, a pair of tracks upon which a cylindrical object may roll, means to hold a pair of forms between said tracks so that the rolling object shall contact with the forms, means for supplying said forms with inks of different colors, means for engaging the upper side of and rolling such object over the forms and said tracks, and yielding means for returning said object-rolling means to its initial position after the object has been rolled beyond the forms.
- 20 25. 11. In a machine for printing cylindrical objects, a pair of tracks upon which a cylindrical object may roll, a support to hold a pair of forms between said tracks so that the rolling object shall contact with said forms, a pair of reciprocatory tracks, yielding means for holding the same a distance above the first-named tracks in excess of the diameter of the cylindrical object, to facilitate the placing of the latter between said tracks, and means whereby pressure may be applied upon and forward movement imparted to said last-named tracks to cause them to engage and roll the object forwardly over said forms; one of said last-named tracks being adjustable toward and from the other.
- 30 35. 40. 12. In a machine for printing cylindrical objects, a pair of tracks upon which a cylindrical object may roll, a support to hold a pair of forms between said tracks so that the rolling object shall contact with the forms, a pair of reciprocatory tracks, yielding means for holding the same a distance above the first-named tracks in excess of the diameter of the cylindrical object, to facilitate the placing of the latter between said tracks, means whereby pressure may be applied upon and forward movement imparted to said last-named tracks to cause them to engage and roll the object forwardly over said forms, and yielding means whereby said pressure applying means and last-named tracks shall be returned to their initial positions.
- 45 50 55 60 65 70 75 80 85 90 95 100
13. In a machine for printing cylindrical objects, a pair of tracks upon which the cylindrical object may roll, a support to hold a pair of forms between said tracks so that the rolling object shall contact with said forms, a pair of reciprocatory tracks, yielding means for holding the same a distance above the first-named tracks in excess of the diameter of the cylindrical object, to facilitate the placing of the latter between said tracks, and means whereby pressure may be applied upon and forward movement imparted to said last-named tracks to cause them to engage and roll the object forwardly over said forms; one of said last-named tracks being adjustable toward and from the other.

In testimony whereof I affix my signature, in presence of two witnesses.

JESSE B. SCOTT.
